UNITED STATES PATENT OFFICE.

GEORGE W. HALL, OF INDIANAPOLIS, INDIANA, ASSIGNOR OF ONE-HALF TO CHARLES S. RAUH, OF INDIANAPOLIS, INDIANA.

CAPILLARY SPRING-OILER.

1,258,672.

Specification of Letters Patent. Patented Mar. 12, 1918.

Application filed July 26, 1917. Serial No. 182,914.

To all whom it may concern:

Be it known that I, GEORGE W. HALL, a citizen of the United States, and a resident of Indianapolis, county of Marion, and 5 State of Indiana, have invented a certain new and useful Capillary Spring-Oiler; and I do hereby declare that the following is a full, clear, and exact description thereof, reference being had to the accompanying 10 drawings, in which like letters refer to like parts.

My invention relates to new and useful improvements in capillary spring oilers and is adapted primarily for use in connection 15 with leaf springs for properly lubricating between the leaves of the spring, and my object is to provide a tubular construction, preferably attached to the spring in pairs.

A further object is to provide an absorbent material for the interior of the tubular member for gradually feeding the oil on to the spring.

A further object is to provide a wick through which lubricant will be fed to the 25 absorbent material by capillary attraction.

A further object is to provide a well at the lower end of each tubular member for containing a supply of lubricant.

A further object is to provide a slot in the 30 wall of the casing through which the lubricant is fed on to the spring.

A further object is to provide means for attaching the tubular members to the spring.

Further objects and advantages will be 35 hereinafter set forth and more particularly pointed out in the accompanying specification.

The full nature of the invention will be understood from the accompanying drawings 40 and the following description and claims:

Figure 1 is a side elevation of a portion of a spring showing my improved oiler attached thereto. Fig. 2 is an enlarged transverse vertical sectional view through the 45 spring showing one of the tubular members in section. Fig. 3 is a detail top plan view of the spring showing one of the tubular members in transverse section. Fig. 4 is an 50 elevation of one of the tubular members removed from the spring.

In the drawings, 1 indicates a spring which may be constructed in any preferred manner, in this instance, an elliptical spring, 55 such as is used in connection with automo-

biles and similar vehicles, said spring being built up of leaf sections 2. In order to properly lubricate the springs to keep the same from emitting a creaking sound and also to prevent the leaves from becoming 60 rusted, I provide my improved form of oiling device comprising elongated tubular members 3 which are preferably mounted in pairs, one on each side of the spring section, although it will be clearly understood that 65 said members may be mounted singly if so desired.

The upper ends of the tubular members 3 are preferably provided with a cap 4, which is threaded on to the tubular member, while 70 the lower ends of the tubular members have threaded thereon, cups 5, which preferably extend a distance below the lower ends of the tubular members to form wells or reservoirs for containing a quantity of the lubricant 75 at the lower ends of the tubular members.

The faces of the tubular members resting against the leaves of the spring, are provided with elongated slots 6, through which 80 the lubricant may pass into engagement with the spring and in order to cause the lubricant to feed slowly and gradually on to the spring, a strip of felt 7, or other similar absorbent material, is introduced into each 85 tubular member either in a single section or substantially in the form of a roll, a portion of the felt projecting through the slot 6 so as to rest against the edge face of the spring. Extending vertically between the folds of 90 the strip of felt 7, is a wick 8 of the ordinary construction, said wick extending the full length of the tubular member so that as the lubricant is absorbed by the felt and dispensed through the slot 6 on to the spring, 95 the wick, through capillary attraction, will continually feed the lubricant to the strip of felt throughout its length so long as any of the lubricant remains within the tubular member and well.

Any suitable means may be employed for attaching the tubular members to the spring, but in this instance, a pair of rods 9 are employed, one above and one below the sections of the spring, said rods extending 105 through bores 10 in the tubular members 3, one end of each rod being threaded to receive nuts 11 which are normally held against reverse rotation by lock washers 12.

As shown in Fig. 1 of the drawings, the 110

tubular members may be positioned at any suitable point along the length of the spring sections as the lubricant will feed lengthwise of the leaves of the spring owing to the 5 vibrating movement thereof. It will likewise be seen that the parts of the oiling device are practically indestructible from use and owing to the slowness at which the lubricant is fed from the oiling device, one filling of 10 the tubular members will suffice for a long period of time, thereby requiring very little attention.

It will likewise be seen that instead of forming the shield into a roll and inserting 15 a wick therethrough the strip of felt may be of a thickness to closely fill the interior of the tubular member when compressed and naturally a portion of the felt will protrude through the slot in the tubular member. 20 When this form of felt is used, the wick is dispensed with.

It will likewise be seen that the well or reservoir at the lower end of the tubular member may be formed integral with the 25 tubular member instead of being threaded thereon.

The invention claimed is:

1. An oiling device for springs, comprising a tubular member having a longitudinal slot, a fabric in said tubular member arranged circularly around the walls thereof for retaining a lubricant and gradually feeding the same through said opening onto 30

the spring, and means to attach the tubular member to the spring.

2. An oiling device for springs, comprising 35 a tubular member having an elongated slot therein, means to close the ends of said tubular member, an absorbent fabric extending longitudinally of the tubular member, 40 and a wick engaging the fabric and extending longitudinally thereof for retaining the fabric saturated with lubricant throughout the length of the tubular member.

3. An oiling device for springs, comprising 45 a tubular member having an elongated slot therein, a cup at the lower end of the tubular member, said cup forming a well below said slot, an absorbent fabric extending longitudinally of the tubular member 50 and adapted to dispense lubricant through the slot on to a spring, and means incased by the fabric through which lubricant may pass from end to end of the fabric by capillary attraction.

4. An oiling device for springs, comprising 55 a hollow member having a slot, means to close the ends of the hollow member, a fabric around the walls of the hollow member, and means incased by the fabric for conveying lubricant from end to end of the fabric by capillary attraction.

In witness whereof, I have hereunto affixed my signature.

GEORGE W. HALL.
